UNITED STATES PATENT OFFICE

LEROY M. LEWIS, OF ROSEMONT, PENNSYLVANIA, ASSIGNOR TO CENTRAL AUTOMATIC SPRINKLER COMPANY, OF PHILADELPHIA, PENNSYLVANIA, A CORPORATION OF DELAWARE

TORRENT VALVE FOR SPRINKLER SYSTEMS

Application filed April 30, 1928. Serial No. 273,390.

My invention relates to valves known as "torrent valves" which are frequently utilized in those types of sprinkler systems in which, upon the opening of one of the 5 sprinkler heads, a solution other than water is initially released and thereafter succeeded by a flow of water from the head. Systems of this character are particularly adapted for use where the sprinkler heads 10 are disposed in buildings or the like in which the temperature conditions are such that if the pipes of the system leading thereto were normally filled with water there would be danger of the latter freezing and thus preventing the proper operation of the heads 15 upon the occurrence of a fire. To obviate this difficulty the system or at least that portion thereof which is exposed to the low temperature conditions is normally filled 20 with some suitable non-freezing solution, such as a solution of calcium chloride, maintained under sufficient head to forcibly issue from one or more of the sprinkler heads upon an opening of the latter but as this 25 solution is necessarily limited in quantity it is desirable to provide means for introducing water under suitable pressure or head to the system after the opening of the heads so that as the non-freezing solution initially 30 released approaches exhaustion the water will then supplement the same and continue to flow from the head for so long a period as may be desired. The function of the torrent valve, therefore, is to provide for the 35 admission of the water to the system after a predetermined quantity of the calcium chloride or other non-freezing solution employed has been released through the opening of one or more of the sprinkler heads.

The principal object of my invention is to provide a torrent valve of improved design and construction and embodying features and advantages not heretofore found in valves intended for a similar purpose; to provide a torrent valve of exceedingly simple form which can be manufactured with a minimum of expense, which is not liable to get out of order or become damaged under conditions of use and which is satisfac-

torily operative for the performance of its intended function.

My invention further includes other objects, advantages and novel features of construction and arrangement of the several elements comprised in the valve as herein-after more specifically mentioned or which will be apparent from the following description of a torrent valve embodying the principles of my invention and illustrated in the accompanying drawing in which Fig. 1 is a vertical central section through the valve and Fig. 2 is a substantially diagrammatic view designed to facilitate a proper understanding of the operation of the valve when installed in a sprinkler system. The same symbols are used to designate similar parts in the two figures, and as the valve is intended particularly for installation in the sprinkler system in upright position as shown in Fig. 1 I shall for convenience consider the valve as disposed in that position when referring to the different parts and the relation which they bear to each other.

The particular embodiment of the valve which I have chosen to illustrate comprises a hollow casing, generally designated as 1, providing a main chamber 2 and an auxiliary chamber 3 generally laterally disposed with respect to the main chamber and communicating therewith. The casing is arranged to provide an inlet 4 leading upwardly into the main chamber 2, the wall of the inlet being desirably upwardly and inwardly inclined, as well as an outlet 5 leading upwardly from the main chamber and vertically aligned with the inlet. To facilitate connection of the valve to the supply line by means of which water is supplied to the inlet 4, the casing may be provided at its lower end with a suitable flange 6 and, similarly, to facilitate connection of the outlet 5 with the line leading to the sprinkler heads the casing may be provided with a flange 7 at its upper extremity.

An annular seat 8 is threaded into the upper end of the inlet for the reception of a main valve clapper 10 which is carried by a generally horizontally extending arm 12 pivoted on a horizontal, transversely extend-

ing shaft 13 carried by the casing, the valve clapper being effective when in lowered or closed position as shown in full lines in Fig. 1 to cut off the flow of water from the inlet into the casing but to permit the same when 5 swung to open or raised position as indicated in dotted lines in said figure. It will be noted the casing is desirably so formed as to provide a recess 14 for the reception 10 of the valve clapper 10 and its supporting arm 12 when fully open so that these parts are then entirely out of alignment with the inlet and outlet ports and thereby in no way interfere with the passage of water through 15 the casing; additionally, the wall of the casing adjacent the recess is preferably so formed that the free end of the supporting arm 12 will not engage therewith until after 20 the arm and clapper have passed over center to the left, thus preventing the valve from closing back on its seat by gravity after it has once been moved to fully open position in consequence of which the valve will remain in such position until it is manually 25 moved to the right past the vertical in the operation of resetting the valve.

The auxiliary chamber 3 of which mention has been made is generally disposed laterally or to one side of the main chamber 2 and on the opposite side of the inlet from 30 the shaft 13; a hand opening formed in the casing wall and leading into the chamber being normally closed by a removable plate 15 held in position by cap screws 16 or in any other convenient way so that by removing 35 the plate access may be conveniently had to the interior of the chamber. Within this chamber is disposed an auxiliary valve clapper, generally designated as 17, which is pivoted for movement in a vertical plane on 40 a transversely extending horizontal shaft 18 disposed in the lower part of the chamber and generally beneath the auxiliary valve clapper. The latter is cooperative with an 45 annular seat 19 surrounding the opening or passage between the main and auxiliary chambers, this seat being preferably disposed in a plane somewhat inclined from the vertical toward the shaft 13 so that when 50 the auxiliary clapper is closed down on its seat it will be correspondingly inclined from the vertical in the direction of the main chamber 2 and thus tend under the action of gravity to remain on said seat, the clapper 55 being preferably provided with a flexible annular gasket 20 of rubber or other suitable material for cooperation with the seat 19, the gasket being held in place by an annular plate 21 removably secured to the under face 60 of the clapper or in any other convenient way. The clapper may also be provided with a counterweight of lead or the like 22 so disposed near the lower part of the clapper as to tend to swing the latter to open 65 position as indicated in dotted lines in Fig.

1 and to hold the valve therein once it has attained such position, the counterweight also acting as a stop to limit its movement to the right by engagement with the bottom of the auxiliary valve chamber 3, as well as with a lug or dog 24 extending in toward the main chamber 2 from the under face of the auxiliary clapper and adapted to bear against the free end of the arm 12 when both clappers are in closed position so as to hold the main clapper 10 on its seat as hereinafter more fully described.

The inlet 4 at a point beneath the main clapper 10 and the auxiliary chamber behind the auxiliary clapper are connected in any suitable way as by a pipe 25 of relatively small diameter extending on the outside of the casing from the inlet to the auxiliary chamber or by means of a passage cored out in the wall of the casing and performing the same function as the pipe, namely, to continuously maintain communication through a relatively restricted orifice between a point beneath the clapper and the auxiliary chamber. If desired the pipe may be provided with a valve 26 to control the flow therethrough.

The auxiliary valve chamber is provided with a drain opening or port 28 in its bottom which may be internally threaded for the reception of a pipe I when the valve is installed in the system, and is of greater effective area than pipe 25.

It will be noted that the area of the back or rear face of auxiliary valve clapper 17 is considerably greater than that of the under face of the main clapper 10 which is exposed through the opening in seat 8 and this is essential in order that the auxiliary valve clapper through coaction of the lug 24 and arm 12 will be effective to hold the main clapper 10 on its seat so as to keep the inlet closed when the fluid pressure beneath the clapper 10 and in the auxiliary chamber 3 is the same, a condition which is normally maintained through the connection effected by the equalizing pipe 25 as will hereinafter more fully appear.

I shall now refer to the preferred manner of installing my improved torrent valve, when constructed substantially as hereinbefore described, in a typical sprinkler system in which a torrent valve may be desirably employed as well as to the operation of the valve when so installed, and for this purpose reference may be particularly had to Fig. 2 in which the essential parts of the sprinkler system which are operatively associated with the torrent valve are diagrammatically shown. Thus the torrent valve 1 is connected through the medium of flange 6 with a supply pipe A extending to a suitable source of water supply maintained under a suitable head or pressure by means of a pump or the like or connected directly

to the city mains if the pressure therein is sufficient for satisfactory operation. The torrent valve is also connected through the medium of the flange 7 with a main pipe 8 B from which branches B' extend throughout the building to the various sprinkler heads C, some or all of which may be located in rooms or the like where the temperature is either normally below the freezing point of water or else sometimes falls below that point so that if the pipes were filled with water there would be danger of their freezing. For containing the solution of calcium chloride or other non-freezing mixture, a tank T may be located in an elevated position so as to afford the required head and connected by a pipe D with the pipe B, shut-off valves E being desirably disposed in pipe D at suitable points for controlling the flow of fluid therethrough. From some convenient point in the main B a smaller pipe F, desirably provided with a control or shut-off valve G, is extended to a valve H of the type commercially known 25 as an "altitude controlling valve" or a "pressure controlling valve" which is connected in and arranged to establish or cut off flow through the drain pipe I extending from the port 28 of the torrent valve to the sewer 30 or other drainage point. Desirably a check valve J is located in the pipe D between the tank and the pipe F operative to permit flow of fluid through pipe D to main B but to prevent the flow thereof in the opposite 35 direction while a check valve K is located in the main B above the torrent valve so as to permit flow of water from the torrent valve into the main above the check valve but to prevent flow from the pipe D into the 40 torrent valve. The various connections having been effected in the manner described, the operation of the system and more particularly of the torrent valve will now be explained: Under normal conditions and 45 with the valve E—E and G open and the sprinkler heads C closed, the pipes leading to the latter will be filled with the non-freezing solution at a pressure or head determined by the position of the tank T, the 50 pressure of this solution acting through pipe F on the control valve H, operating to maintain the latter in such condition that flow of fluid cannot take place through pipe I past valve H. The supply pipe A and inlet 55 4 of the torrent valve are also filled with water under whatever pressure is maintained in the supply pipe A while the auxiliary chamber 3 of the torrent valve is likewise filled with water under similar pressure 60 because of the connection effected between said chamber and the inlet 4 through the equalizing pipe 25. Under these normal conditions, clapper 10 is held tightly closed on its seat through the operation of the lug 65 24 carried by the auxiliary valve clapper 17

which bears on the arm 12 thus preventing any flow of water from inlet 21 into the chamber 2. As the area of the clapper 10 subjected to the water pressure in the inlet is considerably less than the area of the auxiliary valve clapper 17 subjected to the similar pressure in the auxiliary chamber 3, the auxiliary valve clapper thus remains effective to hold the main clapper on its seat so long as the same pressure is maintained beneath the main clapper and in the auxiliary chamber, a condition which exists so long as flow through drain pipe I is interrupted by the control valve H.

However, upon the opening of one of the sprinkler heads C following a predetermined rise in the temperature of the air in its vicinity, the non-freezing solution supplied to the system from the tank T immediately issues from said head or heads and as the fluid pressure in the pipe B and, in turn, pipe F decreases in correspondence with the diminution of the supply of solution in tank T, a point is very quickly reached at which said pressure is insufficient to maintain the control valve H closed, with the result that said valve operates to open pipe I. As the effective area of the port 28 connected with said pipe as well as that of the pipe itself is greater than the corresponding area of the equalizing pipe 25, the water in the auxiliary chamber 3 now begins to drain therefrom more rapidly than it can be supplied thereto by the equalizing pipe 25 so that the pressure acting on the auxiliary valve clapper 17 is very rapidly lowered to a point at which it is no longer effective to overbalance the pressure exerted beneath the main clapper 10 with the result that the main clapper is raised from its seat, thereby forcing the auxiliary valve clapper toward open position, indicated in dotted lines in Fig. 1, to which it is finally carried through the action of the counterweight 22. Meanwhile main clapper 10 has also been swung to open position by the rush of water through the inlet thus clearing the passage from the inlet to the outlet of the torrent valve and permitting the water to flow into main B and branch pipes B'. Although by this time the non-freezing solution is ordinarily nearly exhausted, a certain quantity thereof usually still remains in the tank and pipe D so that for a short period after the admission of water to the pipes B, B' this remaining non-freezing solution will continue to flow thereinto as well so that a mixture of water and non-freezing solution will issue from the open head until all the non-freezing solution is exhausted after which water alone will issue from the head until the flow from the supply pipe to the torrent valve is intentionally shut off, thus leaving the torrent valve with both of its

valve clappers in open position. To reset the clappers of the torrent valve from such position it is necessary to remove the cover plate 15 so the main clapper can be swung down onto its seat by the insertion of a suitable instrument over the upper edge of the auxiliary clapper after which the latter may be manually moved against its seat upon which it tends to remain by reason of its inclination from the vertical. The cover plate may then be replaced and water under low pressure admitted to the inlet from the supply pipe so as to gradually fill the auxiliary chamber through the equalizing pipe without disturbing the adjusted position of the valve clappers; as soon as the auxiliary chamber is filled, the pressure on the supply may be increased since there is then no danger of disturbing the adjusted position of the clappers.

While the check valves J and K are not absolutely necessary, their employment in the positions indicated is desirable since the valve K prevents the main chamber of the torrent valve from filling with the non-freezing solution while the valve J is effective to prevent water from flowing up into the tank following the opening of the torrent valve.

While I have herein described and illustrated a preferred embodiment of my invention with considerable particularity, I do not thereby desire or intend to specifically limit myself thereto as minor changes and modifications may be made in the design construction and arrangement of the various elements without departing from the spirit and scope of the invention as defined in the appended claims.

Having thus described my invention, I claim and desire to protect by Letters Patent of the United States:

1. A valve of the class described, comprising a casing having an inlet and an outlet, a main chamber disposed therebetween and an auxiliary chamber communicating with the main chamber, a main valve clapper pivoted in the main chamber for movement in a vertical plane and operative to control the admission of fluid to said chamber from the inlet, an auxiliary valve clapper of greater area than said main valve clapper horizontally pivoted for movement in a vertical plane in said auxiliary chamber and operative when in one position to close the passage between the main and auxiliary chambers, a lug carried by the auxiliary valve clapper operative to hold the main clapper closed over the inlet when said auxiliary clapper is in said position, and means forming a fluid passage from the inlet to the auxiliary valve chamber operative to maintain the same fluid pressure in the auxiliary chamber as in the inlet when both of said valve clappers are in closed position.

2. A valve of the class described, comprising a casing having an inlet, an outlet aligned therewith, a main chamber disposed between the inlet and the outlet and an auxiliary chamber laterally offset with respect to the main chamber and communicating therewith, a main valve clapper in the main chamber pivoted for movement in a vertical plane and operative to open and close the inlet, an auxiliary valve clapper of greater area than the main clapper disposed in the auxiliary chamber and horizontally pivoted for movement in a vertical plane therein, a valve seat interposed between the main and auxiliary chamber adapted for the reception of said auxiliary clapper and disposed in a plane inclined toward the main clapper, a lug carried by the auxiliary clapper operative to hold the main clapper in closed position when the auxiliary clapper is on said seat, means forming a fluid passage of relatively restricted area between the inlet beneath the main clapper and the auxiliary chamber operative to maintain the same fluid pressure in the auxiliary chamber as in the inlet when the clappers are closed, and a drain port leading from the auxiliary chamber of greater effective area than said last mentioned means whereby fluid can drain from said chamber more rapidly when said port is open than it can be supplied thereto by said last mentioned means.

3. A valve of the class described, comprising a casing having aligned inlet and outlet ports, a main chamber interposed therebetween and an auxiliary chamber laterally offset with respect to the main chamber and communicating therewith, a valve seat at the inner end of said inlet port, a main valve clapper cooperative therewith to open and close the port, an arm supporting the clapper and pivoted to swing in a vertical plane in the main chamber, an auxiliary valve clapper disposed in the auxiliary chamber and pivoted on a horizontal pivot for movement in a vertical plane, a valve seat surrounding the passage between the main and auxiliary chambers, inclined toward the main valve and adapted for the reception of said auxiliary valve clapper, a lug carried by the auxiliary clapper adapted to directly engage said arm to hold the main clapper on its seat when the auxiliary clapper is on its seat, a connection extending between the auxiliary chamber and the inlet at a point beneath the main clapper and forming a fluid passage between the inlet and the auxiliary chamber of relatively restricted size, and a drain port leading from the auxiliary chamber of greater effective size than said connection whereby when said port is open fluid may be drained from said chamber more rapidly than it

can be supplied thereto through said connection.

4. A valve of the class described, comprising a casing having vertically aligned inlet and outlet ports, a main chamber disposed therebetween and an auxiliary chamber laterally offset from the main chamber and communicating therewith, an annular valve seat at the upper end of said inlet port, a pivoted valve clapper movable to and from said seat in a vertical plane and operative to control the admission of fluid from the inlet to the casing, an annular valve seat interposed between the main and auxiliary chambers and inclined from the vertical toward the main chamber, the area of the passage defined by the seat being greater than the area of the passage defined by the first mentioned seat, an auxiliary valve clapper pivoted in the auxiliary chamber adapted to cooperate with the auxiliary valve seat and to move in a vertical plane from closed position on said seat to open position away from said seat, means carried by said clapper operative when the clapper is in closed position to hold the main clapper on its seat, a connection between the auxiliary chamber and the inlet at a point beneath the main clapper affording a fluid passage of relatively restricted area between the inlet and the auxiliary chamber, and a drain port leading from said auxiliary chamber of greater effective area than said fluid passage whereby when said port is open fluid will be drained from said chamber more rapidly than it can be supplied thereto through said passage.

In witness whereof, I have hereunto set my hand this 26th day of April, 1928.
